US00D725287S

(12) **United States Design Patent**
Allen

(10) **Patent No.:** **US D725,287 S**
(45) **Date of Patent:** **** Mar. 24, 2015**

(54) **SHOPPING CART CORRAL HAVING AN ENTRY PORTION TO WHICH ADVERTISEMENTS ARE AFFIXED**

(71) Applicant: **Joseph Allen**, Murrieta, CA (US)

(72) Inventor: **Joseph Allen**, Murrieta, CA (US)

(73) Assignee: **Starlite Media, LLC**, New York, NY (US)

(**) Term: **14 Years**

(21) Appl. No.: **29/432,660**

(22) Filed: **Sep. 18, 2012**

Related U.S. Application Data

(60) Division of application No. 29/405,487, filed on Nov. 2, 2011, now Pat. No. Des. 667,504, which is a continuation of application No. 29/387,041, filed on Mar. 8, 2011, now Pat. No. Des. 653,709, which is a continuation of application No. 29/364,404, filed on Jun. 23, 2010, now abandoned, which is a continuation of application No. 29/314,253, filed on Mar. 17, 2009, now abandoned.

(57) **CLAIM**

The ornamental design for a shopping cart corral having an entry portion to which advertisements are affixed, as shown and described.

DESCRIPTION

FIG. 1 is a top isometric view of a roofed shopping cart corral having an entry portion to which advertisements may be affixed;

FIG. 2 is a side view thereof;

FIG. 3 is a front view thereof;

FIG. 4 is a top view thereof;

FIG. 5 is a top isometric view of a roofed shopping cart corral having an entry portion to which advertisements may be affixed;

FIG. 6 is a side view thereof;

FIG. 7 is a front view thereof; and,

FIG. 8 is a top view thereof.

The broken lines depict portions of the shopping cart corral having an entry portion to which advertisements are affixed which form no part of the claimed design.

1 Claim, 8 Drawing Sheets
